UNITED STATES PATENT OFFICE.

CLIFFORD C. DANCE, OF DENVER, COLORADO.

DESIGN FOR A NOZZLE CASING FOR SUCTION CLEANERS.

Application filed June 8, 1926. Serial No. 17,982. Term of patent 3½ years.

To all whom it may concern:

Be it known that I, CLIFFORD C. DANCE, a citizen of the United States, residing in the city and county of Denver, State of Colorado, have invented a new, original, and ornamental Design for a Nozzle Casing for Suction Cleaners, of which the following is a specification, reference being had to the accompanying drawing, forming part hereof.

Figure 1 is a top view of the nozzle casing for suction cleaner.

Figure 2 is an end view of the same.

Figure 3 is a front view of the same.

The principal feature of the invention is the ornamentation of nozzle case by the raised, triangular shaped central figure.

I claim:

The ornamental design for a nozzle casing for suction cleaners as shown and described.
